(57) **CLAIM**

The ornamental design for an equipment stand, as shown and described.

DESCRIPTION

FIG. 1 is a perspective view of an equipment stand according to the invention;

FIG. 2 is a top view of the equipment stand of FIG. 1;

FIG. 3 is a bottom view of the equipment stand of FIG. 1; and, FIG. 4 is a front view of the equipment stand of FIG. 1.

The broken lines immediately adjacent to the shaded areas represent the boundaries of the claimed design while all other broken lines are directed to unclaimed environment. None of the broken lines form part of the claimed design.

1 Claim, 3 Drawing Sheets

FIG. 1

FIG. 2**FIG. 3**

FIG. 4
